US00D458753S

(12) **United States Design Patent** (10) Patent No.: **US D458,753 S**
Overholt et al. (45) Date of Patent: **** Jun. 18, 2002**

(54) **CONTAINER**

(75) Inventors: **Trenton M. Overholt**, Manhattan Beach; **Gerald R. Koefelda**, Seal Beach; **Roger S. Hsu**, Torrance, all of CA (US)

(73) Assignee: **Rehrig Pacific Co.**, Los Angeles, CA (US)

(**) Term: **14 Years**

(21) Appl. No.: **29/129,827**

(22) Filed: **Sep. 21, 2000**

(51) LOC (7) Cl. **03-01**

(52) U.S. Cl. **D3/304**
